GREETING CARD VENDING MACHINE

Hubert M. Giepen, Chicago, Ill., assignor to Giepen
Associates, Inc., Chicago, Ill., a corporation of Illinois

Filed Sept. 18, 1961, Ser. No. 66,824

Term of patent 14 years

(Cl. D52—3)

The figure is a perspective view of a greeting card vending machine embodying my new design.

The rear and undisclosed side of the vending machine are plain and unornamented.

The broken line portions representing cards and lettering are for illustrative purposes only. The lining on the front of the base portion represents shallow grooves.

I claim:

The ornamental design for a greeting card vending machine, substantially as shown and described.
